MACHINE FOR TRIMMING AND REMOVING BRAID FROM SHIELDED WIRE AND CABLE

Jack C. Rupert, Syracuse, N. Y., assignor to General Electric Company, a corporation of New York

Application November 13, 1950, Serial No. 195,318

2 Claims. (Cl. 30—91)

1

This invention relates to machines for trimming and removing braid from shielded wire and cable to prepare the wire and cable ends for connection to the terminals of electric circuits.

Heretofore the trimming and removing of braid from shielded wire and cable has been a task performed by hand with the use of knives or scissors. Not only does this hand operation usually result in non-uniform and ragged termination of the shields, but also it often results in injury to the insulation surrounding the wire or cable. Moreover, the process is time consuming, particularly since it is sometimes necessary to return and straighten the frayed and uneven braid before a neat appearing, satisfactory termination can be obtained.

Therefore, it is the object of this invention to provide a machine for quickly trimming and removing braid from shielded wire and cable, which leaves a neat, even edge and does not damage the insulation.

The device of this invention accomplishes this aim by cutting the braid by means of a shearing action between a stationary knife blade and a movable knife blade. The insulation is kept clear of the shearing zone by a guide integral with the stationary blade.

For a better and more complete knowledge of this invention reference should be made to the following specification together with the accompanying drawing in which: Fig. 1 is a view partially in section of a preferred embodiment of this invention and Fig. 2 is an end view taken on a larger scale of a portion of the view shown in Fig. 1.

Referring to Fig. 1, a shaft 1 has a crank 2 mounted at its end. The crank 2 is connected by a crank pin 3 to a bearing block 4. One end of a long movable knife blade 5 is secured firmly in a recess 6 in the bearing block 4 by a rivet 7. The upper portion of the long movable knife blade 5 extends through a supporting block 8 in a slide 9 of rectangular cross-section cut therein. The end portion of the movable blade 5 which extends beyond the supporting block 8 contains a recess 10, as shown on a larger scale in Fig. 2. A short stationary blade 11 having an end portion 12 substantially crescent-shaped is held fixed by a pin 13 in the slide 9 of the supporting block 8 juxtaposed to the movable blade 5. The blades are so positioned relative to each other that the crescent-shaped end portion 12 of the stationary blade 11 is adjacent the recess 10 in the end portion of the movable blade 5 with the point of the crescent-shaped portion 12 protruding beyond the

2

edge of the recess 10. Fig. 2 shows this feature drawn to a larger scale. A spring loaded adjusting screw 14 serves to keep the end portions of the blades together.

When shaft 1 is rotated, motion is transmitted through crank 2 and crankpin 3 to bearing block 4, so that bearing block 4 moves in a circular path. The end of long movable knife blade 5 attached to bearing block 4 also assumes a circular motion. The upper portion of movable blade 5, however, can move only in a longitudinal direction since it is constrained from transverse motion by slide 9 of supporting block 8. The upper portion of the movable blade including the end portion 15 containing recess 10 therefore adopts a reciprocating motion.

The transverse motion of bearing block 4 is absorbed by the spring of the portion of movable blade 5 between bearing block 4 and supporting block 8. As the upper portion of movable blade 5 reciprocates, its end portion containing recess 10 moves up and down past the outer edge of the crescent-shaped end portion 12 of stationary blade 11. This produces a shearing action between the edge of recess 10 of the end portion of movable blade 5 and the outside edge of the crescent-shaped end portion 12 of stationary blade 11. The line along which the shearing action occurs is hereinafter called the shearing zone. The point of the crescent-shaped end portion 12 of stationary blade 11 protrudes beyond the shearing zone to act as a guide.

To prepare the shielded cable 15 for trimming, a section 16 of the braid 17 is expanded slightly 35 away from the insulation 18 surrounding the conductors 19 by pushing toward each other the portions of braid 17 adjacent section 16 on both sides. The expanded section 16 of braid 17 is then forced against the point of crescent-shaped end portion 12 of stationary blade 11 so that the point penetrates section 16.

To cut braid 17, cable 15 is now rotated in a clockwise direction, as indicated in Fig. 2, bringing the whole circumference of expanded section 16 into the shearing zone of the blades.

Crescent-shaped end portion 12 of stationary blade 11 acts as a guide as cable 15 is revolved. Conductor 19 and surrounding insulation 18 are kept separate from braid 17 by the point of end portion 12 and pass down and away from the shearing zone as the cable is rotated. Braid 17, however, rides on the upper edge of end portion 12 into the shearing zone at which it is severed. This action of end portion 12 that passes the conductors and insulation on the opposite side of

blade 11 from that at which the shearing action occurs prevents damage to the insulation.

This invention has been described showing one preferred method of imparting motion to the movable knife blade, but many other methods will give equally good results. An eccentric system imparting a longitudinal reciprocating motion to the entire movable knife blade is but one example. The result necessary is that at least the end portion containing the recess, if not all the movable knife blade, move with longitudinal reciprocating motion.

While this invention has been illustrated and described in connection with one preferred embodiment thereof, many modifications will occur to those skilled in the art and it will, therefore, be understood that I intend by the appended claims to cover all such modifications as fall within the true spirit and scope of my invention.

What I claim as new and desire to secure by Letters Patent of the United States is:

1. A machine for trimming and removing braid from shielded wire and cable comprising a stationary knife blade having an end portion substantially crescent-shaped, a movable knife blade having an end portion provided with a recess, said movable knife blade being juxtaposed to said stationary blade to produce a shearing action between the outside edge of said crescent-shaped end portion of said stationary blade and the edge of said recess of said end portion of said movable knife blade upon reciprocating motion of said end portion of said movable knife blade, the point of said crescent-shaped end portion of said stationary blade protruding beyond the zone of

said shearing action to act as a guide, means to support said stationary knife blade and said movable knife blade, and means to impart a reciprocating motion to said end portion of said movable knife blade.

2. A machine for trimming and removing braid from shielded wire and cable comprising a shaft, means for rotating said shaft, a crank mounted at the end of said shaft and rotated thereby, a bearing block attached to said crank by a crank pin and actuated thereby, an elongated movable knife blade secured by one end portion to said bearing block and actuated thereby, said movable knife blade having a second end portion provided with a recess, a short stationary blade having an end portion substantially crescent-shaped, a supporting member constraining a portion of said movable knife blade to move only a longitudinal direction, said constrained portion including said end portion provided with a recess, said constrained portion having reciprocating motion upon rotation of said shaft, said supporting member holding said stationary knife blade juxtaposed to said movable knife blade to produce a shearing action between the outside edge of said crescent-shaped end portion and the edge of said recess in said end portion of said movable knife blade upon reciprocating motion of said constrained portion of said movable knife blade, the point of said crescent-shaped portion of said stationary knife blade protruding beyond the zone of shearing action to act as a guide.
